UNITED STATES PATENT OFFICE.

LOUIS B. GOLDBERG, NATHAN GOLDBERG, WILLIAM GOLDBERG, AND JACOB M. GOLDBERG, OF DENVER, COLORADO.

CAMP STOVE.

Application filed March 3, 1927. Serial No. 172,303.

This invention relates to improvements in the construction of gasoline vapor stoves of the type sometimes referred to as camp stoves.

5 Automobile tourists, hunters, fishermen and others who camp find it a great convenience to be able to dispense with the old fashioned camp fires for cooking and to employ instead a stove that can be conveniently 10 packed for transportation and which employs gasoline as fuel.

It is the object of this invention to produce a gasoline vapor stove that shall be so constructed that it can be conveniently 15 folded into a small package for transportation and which shall be of simple substantial construction.

The above enumerated objects and others that may become apparent as this description 20 proceeds are attained by means of a construction and arrangement of parts that will now be described in detail and reference for this purpose will be had to the accompanying drawing in which the present preferred embodiment has been illustrated and 25 in which:

Fig. 1 is a top plan view showing the stove in operative position, a portion of the grate being broken away to better disclose the 30 construction;

Fig. 2 is a section taken on line 2—2, Fig. 1, parts being shown broken away and the inoperative position of the tank shown by dot and dash lines;

35 Fig. 3 is a fragmentary section taken on line 3—3, Fig. 1;

Fig. 4 is a section taken on line 4—4, Fig. 1 and shows a portion of the priming device; and

40 Fig. 5 is a section taken on line 5—5, Fig. 3, and shows the construction of the valve.

Numeral 1 represents the bottom of the casing 2 and 3 the ends, 4 and 5 the sides, and 6 the cover, while the grate is represented by numeral 7. Secured to the bottom 1 is a burner assembly comprising a manifold 8, two burners 9 and 10 and a mixing chamber 11. The burner assembly is supported by two M-shaped brackets having feet 12, which are perforated for the reception of rivets 13, clips 14 are secured to the vertical end portions of the brackets and have their upper ends bent over onto the burners in the manner shown in Figs. 1 and 55 2. A strap 15 extends over the manifold

and has its ends secured to the brackets. By the means just described, the burners are securely fastened to the bottom.

Secured to the underside of the burner 9 is a bracket 16 formed from a U-shaped strip of metal whose two sides are spaced apart as shown in Fig. 3 and whose extreme ends 17 are spot welded or otherwise secured to the burner 9. The spaced vertical sides are perforated for the reception of the generator tube 18. An L-shaped bracket 19 is secured to the underside of the burner 10 and has a vertical portion 20 which is perforated for the reception of the pin 21.

The fuel is contained in a cylindrical tank 22. Secured to one end of this tank is a rigid pipe 23, which is connected with the generator tube 18 by means of an L 24 which also forms the body of a valve, the rotatable stem of which has been designated by numeral 25. The stem is hinged at 26 and is provided at its outer end with a knob 27. When the stove is not in use, the stem is bent in the manner indicated by dotted lines in Fig. 1. A rod 28 is secured to the other end of the tank 22 and extends therefrom in a direction parallel with the tube 23. The end of this rod is provided with a pin 21 which extends through an opening in the bracket 20 (Fig. 3). It is now apparent that the tank 22 can be rotated about the common axis of the generator tube 18 and the pin 21 from the position indicated by full lines to the position indicated by dotted lines in Fig. 2. The burner assembly is located to one side of the center of the casing so that when the stove is in use, it will occupy the full line position shown in Fig. 2 and when the stove is inoperative, the tank occupies the dotted line position. The upper edge of side 4 is provided with notches 29 and 30 for the reception, respectively, of the tube 23 and the rod 28.

It will be observed that the top of each of the burners has a central depression 31. The depression in burner 9 serves as a priming cup into which a quantity of gasoline is deposited and ignited for the purpose of heating the generator tube 18, which is located directly over this depression.

In order to conveniently convey gasoline from the tank 22 to the priming cup in the burner 9, we have provided the tank with a pipe 32 which extends from the outlet of a valve 33, whose inlet is connected with the

pipe 34 that extends downwardly within the tank and terminates near the bottom thereof. Pipe 32 terminates adjacent the burner 9 and has pivotally attached to it a small metal trough 34'. This trough can occupy the position shown in full lines in Fig. 4 and can also be turned up into the dotted line position. When gasoline is to be transferred from the tank to the priming cup, the trough is moved 10 into the position shown in Figs. 1 and 4 and valve 33 opened; gasoline will now flow from the tank 22 through pipe 32 into the trough 34' and thence into the priming cup 31. When sufficient gasoline has been transferred 15 to the priming cup, valve 33 is closed and the trough turned up into dotted line position (Fig. 4). The gasoline is now ignited and raises the temperature of the generator tube 18 to such an extent that when the valve 24 is opened, the gasoline will be vaporized so that it will enter the mixing chamber 11 as 20 a gas and will become mixed with air so as to form a combustible mixture that will pass through the manifold 8 and into the burners. After the generation of gas has commenced, the gas that emerges through the 25 openings in the top of burner 9 will be ignited and the flame will keep the temperature of the generator tube 18 sufficiently high 30 to maintain the gas supply. At this point attention is called to the fact that the tank 22 contains air under pressure as well as gasoline and that this air tends to force the gasoline outwardly from the tank. 35 The stove has been shown as provided with two burners, one being attached to each end of the intake manifold 8. It sometimes happens that only a single burner is needed and a valve has therefore been provided for 40 controlling the flow of gas to burner 10. This valve is formed by a thimble like member 35, which is secured within the manifold between the mixing chamber 11 and the burner 10. This thimble has its bottom provided with an opening 36. The end of the 45 manifold beyond the thimble 35 has a closure formed by two interconnected cup-shaped members 37 and 38, whose bottoms are perforated for the reception of the valve 50 stem 39, which is slidable and which is guided in its movements by the members 37 and 38. Secured to the inner end of the stem 39 is a cup-like metal member 40, whose sides have a slight taper. Member 40 is 55 of such size that its smaller end will enter opening 36 but its larger end will not. When the stem 39 is moved towards the left (Fig. 5) the opening 36 can be restricted or closed entirely. The gradual taper of the 60 cup 40 permits fine adjustments to be made and also serves to produce the necessary friction to hold the valve in closed position. An extension 41 is pivotally attached to the 65 end of the valve stem at 42 and this can be moved from full line to dotted line position

(Fig. 1) and vice versa, a slot 43 being provided in the end 2 for this purpose.

Tank 22 is provided with a fill opening that is closed by a screw plug 43', which is also provided with a central opening 44, 70 through which air may be pumped into the tank. As the construction of plug 43' is old and well known, it will not be described in detail.

The novel features of this stove are believed to reside in the structure which permits the tank 22 to be rotated about a fixed pivot, from a position, such as shown in Figs. 1 and 2, where the tank lies outside of the casing to the dotted line position, shown 80 in Fig. 2. When the stove is to be transported the tank 22 is positioned within the casing where it will be protected against injury. When the stove is to be used, the cover 6 is first opened, then the grate 7 is 85 raised, after which the tank is rotated from dotted to full line position (Fig. 2), after which the grate is lowered to its operative position. The trough 34' is now adjusted to the full line position (Fig. 4), after which 90 valve 33 is opened for the purpose of allowing gasoline to flow into the priming cup in burner 9. When sufficient gasoline has been transferred to the priming cup, valve 33 is closed and the trough turned up into dotted line position (Fig. 4). The gasoline is 95 now ignited and the flame heats the generator tube 18. When the gasoline has been nearly consumed, valve 27 is opened thereby allowing gasoline to flow through the tube 100 18 and become vaporized.

Special attention is called to the means employed for transferring gasoline from the tank to the priming cup and especially to the trough that can be moved away from the flame when not in use. The specific arrangement illustrated is merely illustrative of a priming device for transferring gasoline from the tank to the priming cup and which comprises means movable with respect to the 110 burner and priming cup.

A baffle plate 45 is provided between the burner 9 and the valve 24 to protect the latter from the heat.

It is apparent that the valve stem 25 will 115 not be rotated the same amount every time the valve is closed and the pivotal connection 26 is therefore formed from two interconnected eyes so that the outer end of the stem will have a universal movement with respect to the part that is fastened to the stem; this permits the knob to hang downwardly at all times.

It is obvious that if the burner assembly is 125 secured to the bottom 1 in such a way that it can slide towards the side 4, that the casing can be made narrower than when the feet 12 are riveted to the bottom in the manner shown as such a construction permits the burner assembly to be moved towards the 130

side 4 when the stove is folded for transportation.

In Fig. 5 the preferred construction of the valve mechanism has been illustrated and has been described above. Special attention is directed at this point to the fact that an asbestos washer is located between members 37 and 28. This washer serves two purposes, in the first place it acts as a gasket and prevents the escape of combustible vapor at this point and in the second place it acts as a lubricator. When gasoline containing vapors come in contact with the washer they condense and the gasoline is absorbed and soon accumulates to such an extent that a film of gasoline will be deposited on the stem 39 when it is moved and this prevents the stem from rusting.

Having described the invention, what is claimed as new is:

1. In a camp stove, a casing member, a burner assembly, a fuel tank having a generator tube, a bracket secured to one end of the burner assembly, said bracket having an opening through which the tube extends and in which it may be rotated so as to enable the tank to be swung to a position wholly within or without the casing.

2. In a camp stove, in combination, a casing member, a burner assembly secured to the casing member, a perforated bracket secured to each end of the burner assembly, a fuel tank, a pipe secured to one end of said tank, a generator tube extending through one of said perforated brackets, an L connecting said pipe and generator tube, a rigid member connecting the other end of the tank to the other perforated bracket and a pivotal connection between said rigid member and the bracket.

3. In a camp stove, a casing member, a burner assembly located within the casing and secured thereto, a fuel tank having a vaporizer tube rigidly connected thereto and extending substantially parallel therewith, a rigid bar secured to the other end of said

tank, said bar having a pin whose axis is substantially parallel with the axis of the tank and means comprising two perforated brackets, rigidly secured to the burner assembly for providing a hinged connection whereby the tank may be rotated about the axis of the generator tube from a position without the casing to a position within the casing.

4. In a camp stove, a casing member, a burner assembly rigidly secured therein, said assembly having two burners, a fuel tank, a generator tube extending parallel with the axis of the fuel tank, said generator tube lying above one of said burners, means for rotatably connecting the generator tube with the burner, means comprising a rigid link for pivotally connecting the other end of the tank with the other burner, the burner underneath the generator tube having a priming cup and means for transferring fuel from the interior of the tank to the priming cup.

5. In a camp stove, a casing member, a burner assembly rigidly secured therein, said assembly having two burners, a fuel tank, a generator tube extending parallel with the axis of the fuel tank, said generator tube lying above one of said burners, means for rotatably connecting the generator tube with the burner, means comprising a rigid link for pivotally connecting the other end of the tank with the other burner, the burner underneath the generator tube having a priming cup and means for transferring fuel from the interior of the tank to the priming cup, said last named means comprising a valve controlled pipe which extends from a point within the tank to a point adjacent the burner and a movable extension pivotally secured to the outer end of said pipe.

In testimony whereof we affix our signatures.
